CLASSIFYING LINER FOR BALL MILLS

Fernando Falla, 59 Elm St., Millburn, N.J.

Filed June 26, 1958, Ser. No. 744,727

9 Claims. (Cl. 241—183)

The invention relates to a novel liner for the rotating cylinder of ball mills, more especially to a liner which will admit of satisfactory classification of the grinding media for the material to be comminuted within said cylinder, as well as of the material itself.

It has for an object to provide a novel construction of the ring elements forming the liner and to afford a novel arrangement of the same within the cylinder, whereby greatly to increase the efficiency of the grinding operation in securing a fine powder of the raw material, as for example, in the case of Portland cement, as well as for use in the ceramic and mining industries.

Heretofore, the customary and most acceptable mills comprised a cylindrical shell adapted for the rotation, on axially-extending tubular trunnions of relatively large diameter which admit the material, to be pulverized, at one end of said shell and discharge it at the other end. The interior of such cylindrical shell is, to this end, partly filled with balls of hard material but which is softer than the liner material. As the cylinder is designed to rotate at a velocity below the critical centrifugal speed of the balls, the latter are made to cascade on one another—the liner to this end being provided with horizontal vanes or grooves to prevent the ball charge from sliding on the surface of said liner.

For best results, the ball charge must be made up of balls of different diameters, the larger diameter balls serving to break the larger particles of the material to be ground and the smaller ones pulverizing the resulting particles of reduced size—said larger balls being caused to progress toward the feed end of the cylinder and the smaller ones toward the discharge end thereof.

As all of the balls become smaller in the course of the grinding, it is desirable that provision be made whereby they will be caused to accumulate at the discharge end of the mill for replacement by larger diameter balls. With the known type of ball mills such accumulation and replacement is not possible; and it is a further object of the invention to provide a liner which is constructed such that the balls, which have worn to a reduced size, will travel toward and accumulate at the discharge end of the mill.

A still further object of the invention is to provide a liner construction whereby a heavy accumulation of the balls may be avoided at both ends of the mill.

In the operation of grinding, two types of ball mills are generally utilized, viz: the overflow and the air-swept; and the novel liner arrangement set forth is particularly applicable to both. Thus, in the case of the former type, the cavities provided in the novel liner blocks function to deliver the finer particles to the discharge end of the mill, thereby expediting the pulverizing activity to clear faster the final pulverized material. With the air-swept type of ball mill, any residual finely pulverized material in a cavity will be cleared into the path of air supply through the mill to enhance its efficiency.

The novel construction is particularly adapted to the operation of extremely long ball mills which require

2

perforated partitions to retain the various-sized balls in their respective locations. Classification with the novel design of the blocks of the ring liner elements eliminates the use of such partitions, as well as access doors to permit inspection and replacement of the proper size balls in the different compartments.

In carrying out the invention, a succession of laterally contacting ring elements constitutes the liner for the inner surface of the ball mill cylinder, as is the general practice; but, in accordance with the invention, the inner surface of the respective ring elements is so modified as to isolate, when the cylinder is rotated, larger balls to the entrance portion of the mill and to clear small balls to the outlet end. Moreover, the construction is such that the material in process of grinding (smaller ground-up particles) is classified, viz: directed toward the discharge end of the mill for delivery. Pairs of surface pockets or cavities of differing diameters and depths are, to this end, provided in a raised, inclined surface of a block or blocks of which the ring elements are constituted; and the two pockets of a pair are arranged to merge with each other, as set forth. Moreover, surface grooves from the respective pockets serve as discharge channels for temporarily retained balls. The top flat surface provided on a liner ring element, also, may be pitched downwardly in a direction opposite the rotation direction of the cylinder. Guide means are provided on a liner element in advance of said pockets to prevent balls already lodged therein from being struck.

The enhanced efficiency of operation in utilizing the novel liner construction results in a material reduction in power consumption per ton of ground material; and a substantial cost reduction—up to 30%—may be effected.

The nature of the invention, however, will best be understood when described in connection with the accompanying drawings, in which:

Fig. 1 is a longitudinal section through a ball mill equipped with the novel liner, and indicates also the drive mechanism for the same.

Fig. 2 is a transverse section through the mill taken on the line 2—2, Fig. 1 and looking in the direction of the arrows.

Fig. 3 is an isometric view of the block element of novel design and of which the ring liner elements are composed.

Figs. 4 and 5 are, respectively, a front view and a transverse section, taken on the line 5—5, Fig. 4, looking in the direction of the arrows, of said block element.

Fig. 6 is a longitudinal section through a ball mill equipped with the novel liner and Fig. 7 a fragmentary developed view illustrating a modification in the arrangement of the blocks making up a liner ring element.

Referring to the drawings, more particularly to Figs. 1 and 2 thereof, the ball mill comprises the conventional ball-retaining cylinder portion 10 which is mounted for rotation on hollow end-bearings 11, 12, the former being designed to receive, through a feed spout 13 connected thereto, a charge of material to be crushed and ground in the mill. At the opposite and outlet end the comminuted product is designed to be discharged through a discharged spout 13' connected with the hollow end bearing 12—in a manner well understood in the art.

Rotation of the cylinder 10 is conveniently effected from an electric motor 14 through intermediate gearing 15.

The liner for said cylinder 10, however, is of novel construction operating to enhance the efficiency of the grinding action as well as extending the useful life of ball elements effecting the crushing and grinding of the material fed into said cylinder. Said liner to this end comprises a plurality of ring elements 20 disposed adja-

cently longitudinally of the cylinder 10 to fit tightly over its inner surface, each element consisting of a plurality of interlocking blocks 21 of conventional inner surface and one or more blocks 22 constructed in accordance with the invention. That is to say, reference being had to Figs. 3 to 5, the exposed working surface of a block 23 is of an undulating nature (Fig. 5) but includes an intermediate plane surface portion 24 which is preferably pitched (as shown) in a direction opposite to the rotation direction of the cylinder 10.

The various ring elements may be assembled and fixed to the cylindrical shell 10, for example, by bolting the same thereto through intermediate wedges 25 included between a pair of blocks and nuts 26.

Balls 30, 31 for crushing and grinding purposes are indicated and their action is to be controlled in a novel manner, the direction of rotation of the cylinder 10 being in accordance with the arrow indication, Fig. 1.

The aforesaid plane surface 24 in accordance with the invention is recessed to afford two cylindrical and merging hemispherical cavities 32, 33 of different diameters, the former cavity 32 being the smaller and the depth of the same being greater than that of the cavity 33 of larger diameter. Furthermore, there extend outwardly from the respective cavities 32, 33 grooves 34 and 35 which diverge from each other in being directed oppositely to the cylinder rotation; and said grooves are designed to release balls of smaller size toward the discharge end of the mill and of larger size toward its feed end, respectively.

In addition, the leading wall of the intermediate plane surface portion 24 is provided with a wedge-shaped portion 36 lying in a plane perpendicular to the longitudinal axis of the cylinder and oppositely to the discharge grooves. The sides 37, 38 of said portion are differently sloped for the purpose of guiding some of the balls laterally in order to avoid collision with a ball already lodged in a cavity for classification.

Various combinations of the ring liner elements are possible depending on the size and type of material to be operated and also on the length of the mill cylinder over which the operation is conducted. Thus, as is indicated in Fig. 1 of the drawings, all of the classifying ring elements 20, with the exception of two at the respective ends which are provided with a single cavity 33' and 33" respectively, are provided with double cavities—all sets being diametrically disposed and aligned longitudinally along a line parallel to the longitudinal axis of the cylinder.

The two end rings, however, are equipped with only the cavities of larger diameter in order to avoid a heavy accumulation of balls at the mill ends and to maintain a free inlet and outlet for the material to be pulverized and the pulverized material, respectively. It is also conducive to the maintenance of a higher ball level or charge within the mill with consequent increase in capacity.

In some instances, as with the pulverization from fines to super-fines, the end liners may be entirely free of cavities, particularly where the difference in ball sizes is not required to be large.

Instead of a single row only of the cavity pairs at diametrically opposite portions of the liner elements, several parallel rows 40, 41, 42 of the same may be provided along the succession of ring elements—reference being had to Fig. 7 of the drawings—with the pairs 40', 41' and 42'; and in which case, every other ring along a row omits a pair, the pairs of adjacent rows thus being staggered relatively to each other.

In the case of a very long mill—some mills being as much as 36 feet to 40 feet long—it will be advantageous to classify more than two sizes of the balls. In accordance with the invention, it is possible to maintain readily the proper size balls generally at the most suitable location and so increase the efficiency of the mill. In the present practice, mills of such length are equipped with perforated partitions in the attempt to retain the proper

size balls in the selected compartment. This, however, does not prove successful since there is no way to keep the small balls in the final compartment, as well as larger balls, as they wear down, from jamming in the perforations of the partitions, which serve merely to prevent passage of large balls in the first compartment—the return of small balls thereto not being prevented.

Furthermore, to load the compartments it becomes necessary to shut down the mill to allow for opening of the compartment doors. This is not necessary with the novel combination set forth, in that replacement only of large balls at the feed end of the cylinder is required, together with the feed of material. The novel mill operates to classify automatically the balls which, when they become small enough and worn out will have been classified to the section selected by the liner elements in that section.

Referring to Fig. 6 of the drawings, the ball mill cylinder 45 is shown as having a number of the ring liner elements 46 at the feed end 47 of the mill free of cavities and discharge grooves, and similarly at the discharge end 48.

Moreover, provision is made with respect to the arrangement of cavities and discharge grooves over the remaining ring liner elements to classify three sizes of balls—large, medium and small, the large balls 50 being classified toward the feed end by action of the cavities 51; the medium size balls 52 toward the intermediate portion of the mill by the action of the cavities 53, 54; and the smallest balls 55 toward the discharge end by the action of the cavities 56.

The operation of the novel classification arrangement is substantially as follows:

As the mill cylinder rotates with the standard ball charges, the balls keep on cascading into each other, as per level indicated in Fig. 1, because the speed of the mill is to be maintained slightly below the critical centrifugal speed of rotation which would keep the balls against the lining of said cylinder. In so doing, many balls work their way into the larger cavities. If the ball is large enough to fill such large cavity, it will remain there until the mill rotation gives the ball a position to cause it to fall off the liner by the action of gravity. At this moment, the ball cannot do anything but to follow the corresponding discharge groove which directs said ball to the feed end of the mill.

If a smaller ball works its way into the larger cavity it will automatically fall to the bottom of said cavity. It cannot, however, remain there if it is smaller than the associated smaller cavity because when the classifying portion of the liner is at the bottom of the mill, the ball will follow the corresponding groove to the bottom of the smaller cavity and be forced by the discharge channel toward the discharge end of the mill.

I claim:

1. A classifying liner for the rotating cylinder of ball mills comprising a succession of ring liner elements including a plurality of interlocking blocks having an inwardly directed undulating surface, and a selected block of a ring liner element being provided with a pair of merging hemispherical cavities of different diameters and respective integral discharge grooves, the said grooves diverging in a direction opposite to the cylinder rotation.

2. A classifying liner for the rotating cylinder of ball mills according to claim 1, wherein the respective cavities of a block are of different depths.

3. A classifying liner for the rotating cylinder of ball mills according to claim 1, wherein the depth of the cavity of lesser diameter is greater than that of the cavity of greater diameter.

4. A classifying liner for the rotating cylinder of ball mills according to claim 1, wherein a pair of diametrically oppositely-disposed blocks of a ring liner element are provided with the cavities and associated discharge grooves.

5. A classifying liner for the rotating cylinder of ball mills according to claim 1, wherein the cavities and discharge grooves of the ring liner elements adjoining the discharge end of the mill are of lesser diameter than the diameter of the cavities and discharge grooves of the liner elements adjoining the feed end of the cylinder.

6. A classifying liner for the rotating cylinder of ball mills according to claim 1, wherein a plurality of ring liner elements at the respective ends of the liner only are provided with a single cavity and corresponding discharge groove directed toward the middle of the mill. 10

7. A classifying liner for the rotating cylinder of ball mills according to claim 1, wherein the succession of ring liner elements are disposed adjacently longitudinally of said cylinder, and the selected ring element is provided with a plane portion having a pair of merging, ball-receiving cavities discharge grooves laterally and oppositely directed to the cylinder rotation. 15

8. A classifying liner for the rotating cylinder of ball

mills according to claim 7, wherein the block of a selected ring liner element has an integral, wedge-shaped extension of the plane portion directed oppositely to the discharge grooves.

5 9. The classifying liner for the rotating cylinder of ball mills according to claim 8, wherein the inclined sides of the wedge-shaped extension are of different inclinations.
